[57] CLAIM

The ornamental design for a motorcycle fairing, as shown and described.

DESCRIPTION

FIG. 1 is a right side elevational view of a motorcycle showing my new design;

FIG. 2 is a left side elevational view thereof;

FIG. 3 is a front elevational view thereof;

FIG. 4 is a rear elevational view thereof; and

FIG. 5 is a top plan view thereof.

The fragmentary broken line representation of a portion of a motorcycle in FIGS. 1 and 2 is for illustrative purposes only and forms no part of the invention.

FIG. 1

FIG. 2

FIG. 3

FIG. 4

FIG. 5
